UNITED STATES PATENT OFFICE.

JOHN GIRARD, OF NEW BRITAIN, CONNECTICUT, ASSIGNOR TO LANDERS,
FRARY & CLARK, OF SAME PLACE.

DESIGN FOR DRAWER-PULL.

Specification forming part of Design No. 7,454, dated May 26, 1874; application filed May 11, 1874.
[Term of Patent 7 years.]

CASE C.

To all whom it may concern:

Be it known that I, JOHN GIRARD, of New Britain, in the county of Hartford and State of Connecticut, have invented a new Design for Drawer-Pull; and I do hereby declare the following, when taken in connection with the accompanying drawings and the letters of reference marked thereon, to be a full, clear, and exact description of the same, and which said drawing constitutes part of this specification, and represents a perspective view.

This invention relates to a design for a drawer-pull of that class in which the pull is pivoted in a socket, and which are raised to pull open the drawer and left free to drop down into substantially a vertical position; and it consists in the peculiar configuration of the parts, as shown in the accompanying illustration and hereinafter described.

The base is of conical form, with the socket on its apex. In the socket is hung a loop, its sides parallel, running together in semicircular form at the free end. This loop forms the pull. In a state of rest it hangs vertically; but, to pull open the drawer, it is raised, as shown in broken lines.

I claim as my invention—

The design for drawer-pull, consisting of the conical base and socket, with a loop hung in the socket, as described, and shown in the accompanying illustration.

JOHN GIRARD.
